UNITED STATES PATENT OFFICE.

WILLIAM SPEIRS SIMPSON, OF LONDON, ENGLAND.

FURNACE FOR MELTING AND ALLOYING METALS IN VACUO.

1,118,820.

Specification of Letters Patent.

Patented Nov. 24, 1914.

Application filed March 26, 1913. Serial No. 756,977.

To all whom it may concern:

Be it known that I, WILLIAM SPEIRS SIMPSON, a subject of the King of Great Britain, residing at London, England, have invented 5 certain new and useful Improvements in Connection with Furnaces for Melting and Alloying Metals *in Vacuo*, of which the following is a specification.

The object of this invention is to provide 10 a suitable apparatus or furnace for melting, refining and alloying metals which have a lower melting point than iron, and particularly such metals as aluminium and its alloys which it is desirable to heat (and 15 super-heat) *in vacuo*, to prevent oxidation and to facilitate the diffusion of the alloying metals.

In carrying out the purposes of my invention I construct of steel or cast iron, a 20 melting chamber lined with fire brick and provided at the bottom with a series of atmospheric gas burners for supplying the necessary heat, also containing a steel or cast iron melting pot or crucible provided 25 with a cast iron cover so fitted and furnished with means of sealing that it may be held in position by atmospheric pressure while the vacuum chamber thus formed is in operation, the whole apparatus being mounted on 30 trunnions to enable the molten contents of the crucible to be conveniently discharged. The cover of the crucible contains one or more eye pieces inset with glass to enable the operator to view the contents thereof, 35 and is also provided with a receptacle composed of refractory material or of iron, operated by a sliding rod through the top of the cover, whereby various alloying metals or purifying materials may be added to the 40 molten charge in the crucible, without breaking vacuum.

The apparatus is provided with suitable connections for a vacuum pump and with flexible tubes or couplings for the gas sup- 45 ply.

My invention will be clearly understood from the annexed drawings in which:—

Figure 1 is a side sectional elevation of the apparatus. Fig. 2 is a plan of the pre- 50 ferred form of gas burner.

The melting pot or crucible *a* is of steel

or cast iron and is inclosed and supported by the brick lined casing *b* which in turn is mounted by axles on the trunnions *c*. The cover *d*, which is also of cast iron, is 55 provided with two or more eye-pieces *e* and has connected to it a valved pipe *s* leading to the suction pump. The rod *f*, with the stirrup-shaped receptacle or carrier *g*, is provided to enable any material contained 60 in said receptacle to be introduced into the molten contents of the crucible at any desired time and without impairing the vacuum. The joint between the crucible and cover is made by means of the tongue *h* 65 on the edge of said crucible and the asbestos packed groove or recess *k* in said cover. This is found to make a very efficient joint, the cover being held in position by no other means than the external air pressure. An 70 ordinary atmospheric gas burner composed of straight tubes *l* shown in plan, in Fig. 2, is used as the heating medium, this burner being attached directly to the bottom of the casing. This method is found to be superior 75 to a circular burner as regards obtaining an even heat. The exit of flue gases takes place through six or more apertures *m* distributed around the top of casing *b*. The molten metal is removed from the crucible *a* by removing 80 the cover *d*, disconnecting the gas supply pipe *n* by means of a coupling *p* and then tilting the whole apparatus, allowing the molten metal to flow into a suitable ladle.

What I do claim as my invention and desire to secure by Letters Patent is:—

1. A furnace for melting, refining and alloying metals consisting of an open-ended casing having a plurality of exits for flue gas distributed around its top; a support 90 for said casing; a crucible positioned in said casing and resting on the said top thereof; a cover on said crucible having a suction pipe connected thereto; means for introducing alloying metals into the molten 95 charge in the receptacle during the maintenance of the vacuum; and a gas burner attached directly to the bottom of said casing.

2. A furnace for melting, refining and alloying metals consisting of an open-ended 100 casing having a plurality of exits for flue gas distributed around its top; a support

for said casing; a crucible positioned in said casing and resting on the said top thereof; a cover on said crucible having a suction pipe connected thereto; and a gas burner attached directly to the bottom of said casing.

In testimony whereof I have hereunto set

my hand in presence of two subscribing witnesses.

WILLIAM SPEIRS SIMPSON.
